UNITED STATES PATENT OFFICE.

GEORGE J. H. GOEHLER, OF BUFFALO, NEW YORK, ASSIGNOR TO THE CARY
SAFE COMPANY, LIMITED, OF SAME PLACE.

SAFE-DOOR.

SPECIFICATION forming part of Letters Patent No. 436,411, dated September 16, 1890.

Application filed May 15, 1890. Serial No. 351,916. (No model.)

To all whom it may concern:

Be it known that I, GEORGE J. H. GOEHLER, of Buffalo, in the county of Erie and State of New York, have invented certain new and 5 useful Improvements on Doors for Fire-Proof Safes and Vaults; and I do hereby declare that the following description of my said invention, taken in connection with the accompanying sheets of drawings, forms a full, clear, 10 and exact specification, which will enable others skilled in the art to which it appertains to make and use the same.

My present invention relates to doors for fire-proof safes and vaults, its object being to 15 provide a shield or plate which will effectually protect the combination-lock and other locks from all drilling or punching from the outside, thereby rendering it impossible to open a fire-proof safe or vault in the easy 20 manner in which they are now opened.

It consists, essentially, in the novel and peculiar combination of parts and details of construction, as hereinafter first fully set forth and described, and then pointed out in 25 the claim.

In the drawings already mentioned, which serve to illustrate my said invention more fully, Figure 1 is a section of a safe-door, showing a metal plate attached to the inner 30 surface of the door upon which a combination-lock is adjusted, having a metal box-covering. Fig. 2 is a similar part of a safe-door, showing a section of the metal plate with the combination-lock adjusted. Fig. 3 is an in- 35 side view of the combination-lock with box-covering adjusted to the metal plate. Fig. 4 is an inside view of the metal plate without the combination-lock.

Similar letters refer to similar parts throughout the several views.

A represents the knob and dial of a combination-lock.

B is the outside plate of metal of an ordinary fire-proof safe or vault.

C is a plate of metal constructed of alternate layers of welded steel and iron of any desirable thickness. This metallic plate C is welded or otherwise attached to the inner surface B, and upon this plate the combination 45 or other lock is adjusted. It may extend over the entire inside surface of the door or may 50

just cover enough of the inside surface of the door to fully protect all parts of the combination or other lock from drill, punch, or other tools operated from the outside of the safe. 55

D represents the various combination-wheels of a combination-lock constructed in the usual manner. These are attached to the metal plate C by means of a pin a, upon which they revolve. The pin a screws firmly into a 60 threaded opening b in the metal plate C. The threaded opening b extends only part way through the plate C, as shown in Fig. 2.

E is a metal rod connecting the knob A with the cog-wheel c, by means of which the 65 knob A revolves the cog-wheel C, which in turn revolves the cog-wheels e and f, thus revolving the combination-wheels in the usual manner. The cog-wheel e revolves upon the pin g, which screws firmly into a screw- 70 threaded opening i in the plate c. These threaded openings i and b extend only part way through the plate C, as shown in Fig. 2, the only opening extending through the plate C being h for the metal rod E, connecting the 75 knob A with the cog-wheel c.

H is a metal box-covering, which fits closely over the combination-wheels D and cog-wheels c e f.

Having described my invention, what I 80 claim as new, and desire to secure by Letters Patent, is—

In a fire-proof safe or vault, the combination, with the safe-door, of plate of welded steel and iron secured together and hardened, as described, and provided with an opening for the passage of the spindle for the knob, and with internally-screw-threaded recesses for the reception of the studs for the combination-wheels, the spindle, the studs, 85 the combination-wheels, and the casing, said plate being attached to the inner surface of the door and the casing removably affixed to the plate, as set forth.

In testimony that I claim the foregoing as 95 my invention I have hereto set my hand in the presence of two subscribing witnesses.

GEO. J. H. GOEHLER.

Attest:

MICHAEL J. STARK,
WM. O. STARK.
